UNITED STATES PATENT OFFICE.

SILAS B. BROWN, OF CINCINNATI, OHIO, ASSIGNOR TO THE EDWARDS MANUFACTURING COMPANY, OF CINCINNATI, OHIO, A CORPORATION OF OHIO.

TOY REPEATING-RIFLE.

1,381,449.

Specification of Letters Patent. Patented June 14, 1921.

Application filed October 13, 1919. Serial No. 330,238.

To all whom it may concern:

Be it known that I, SILAS B. BROWN, a citizen of the United States, and residing at Cincinnati, in the county of Hamilton and 5 State of Ohio, have invented a new and useful Improvement in Toy Repeating-Rifles, of which the following specification is a full disclosure.

My invention relates to a toy repeating 10 rifle, adapted to fire the conventional fulminate tape.

One of the objects of the invention is to provide a perfectly safe, internal fire, toy repeating rifle, in which the explosion products are confined and directed for escape 15 through the rifle barrel, provision being also made for the external discharge of the exploded tape.

Another object of the invention is to provide 20 a toy rifle structure and mechanism for holding and operating a unitary tape-holding, feeding and cap-firing mechanism of the self-cocking type.

Another object of the invention is to provide 25 a toy which is simple, inexpensive, light, durable and readily manufactured and assembled on a large quantity output basis.

The features of the invention will be more 30 fully set forth in the description of the accompanying drawings, forming a part of this specification, in which:

Figure 1 is a vertical sectional view of the breech of my gun, the firing mechanism being shown in elevation.

35 Fig. 2 is a top plan view of the same, the barrel being removed.

Fig. 3 is a side elevation of my complete gun.

Fig. 4 is a reverse plan of the barrel.

40 Fig. 5 is a front end view of the same.

Fig. 6 is a horizontal sectional view on line 6, 6, Fig. 3, showing the crimped end of the forward end of the barrel.

Fig. 7 is a vertical sectional view of the 45 same on line 7, 7.

The specific type of tape-feeding, firing, trigger and hammer mechanism is not of the essence of the invention, provided that it be a unitary member adapted for inclosure 50 and co-operation with a rifle breech.

For convenience of illustration and as a preferred embodiment, I have shown as this unitary, repeating tape-firing mechanism, the skeleton holding frame, tape-supporting, 55 feeding, trigger and hammer mechanism

fully disclosed in my prior Patent No. 1,250,425, dated Dec. 18, 1917, the detail description of which is not essential to the understanding of the present invention.

This unitary body comprises the skeleton holding frame 1, a trigger 2, and hammer 3, arranged for self-cocking, ammunition tape roll 4, tape feeding mechanism 5 operated by the trigger, the exploded tape issuing from the forward anvil extension 6 of the frame.

This unit is assembled into a wooden rifle stock 7, having a hollowed breech chamber 8, of appropriate shape and dimensions, open at one side and having the lower portion formed with the opening 9, through which the trigger projects, one side of the breech being wholly open. These bottom and side openings are substantially closed by a swivelled breech plate 11, except where the trigger projects, and an opening 12 provided for the escape of the exploded tape. The upper wall of the breech chamber is formed with a vertical slot 13 to be inclosed by the semi-cylindrical rear end section 14, of the rifle barrel 15, the forward end 16 of which is wholly cylindrical.

This rifle barrel is formed of light sheet metal rolled as indicated, with its bottom edges 17 overlapping, see Fig. 7, to form the front end of the barrel, the rear end being formed by the section 14 closing over the breech slot 13.

The front end of the stock is formed with the semicircular groove 18 for the endwise insertion of the rear end 19 of the lower half of the front end 16 of the barrel, holding the barrel to the stock at the front end, the rear end being secured by tack 20. This, while a very simple, inexpensive and convenient assemblage securance, is sufficient to firmly unite barrel and stock.

The side opening of the breech for loading, is preferably on the left hand side of the rifle, the breech plate 11 being pivoted to the stock at its forward end 21.

The bottom portion of this plate is contoured to engage around the bottom of the stock under the firing unit, its rear extremity having an extension piece 22 engaging upwardly over the right hand side of the stock at the breech and terminating in a lip 23 in position to be engaged by the thumb when the hand is in firing position, thus simulating in a degree the self-loading breech piece 105 110

of an actual repeating rifle. This extension piece has a clamp-fit over the adjacent stock portion to hold the plate 11 normally closed. This serves to wholly incase the firing zone, 5 permitting the outward escape of explosion particles, which follow the normal opening provided by the barrel. The breech is thus readily opened up for loading, adjusting or cleaning, and may be securely closed, rendering 10 the toy absolutely safe if properly used.

The margins of the front end of the barrel are upset to form the rounded muzzle end 24, see Fig. 5, which formation also imparts structural permanence and rigidity 15 to the muzzle end, increasing the rifle-like appearance and avoiding sharp ends liable to cut the hand.

The skeleton frame and firing mechanism are so formed that the loading can only 20 be from one side, which is, of course, the left side adjacent the closure plate 11.

This toy is simple, light and inexpensive, yet durable, entirely safe, and constitutes 25 a very attractive toy imitation of a modern repeating rifle.

The invention is not concerned with the type of the firing unit, except where specific characteristics necessitate corresponding characteristics of the breech, such as the 30 correlation of the loading side of the unit and the closure plate, the tape-ejecting provision, and the like, which will be appropriately particularized in the claims.

For loading, the swiveling plate is opened 35 up, the coil of tape is placed on the bearing 40, the resilient tape guide support 41 is accessible and may be depressed by the finger. Feed the advancing end of the tape forwardly over the anvil with the tape adjusted properly, after which the swiveled 40 plate is returned and the rifle is ready for use.

Having described my invention, I claim:

1. In a toy repeating rifle comprising a 45 stock member having a recess in one side of its free end, a barrel formed of sheet metal secured upon the fore end of said stock and having an open under side for communication with said recess, a unitary 50 ammunition tape feeding and exploding mechanism mounted in said stock recess, and a closure for said recess.

2. In a toy repeating rifle, the combination 55 of a rifle stock formed with a breech chamber open at one side and at the bottom, and ammunition tape feeding and firing mechanism mounted in said breech chamber, adapted for loading from the open side of the breech, a swivel breech member on the stock for opening and closing said breech chamber, a rifle barrel secured in the breech 60 portion of the stock and having its rear end forming the upper portion of the breech chamber.

3. In a toy repeating rifle, the combina-

tion of a rifle stock formed with a breech chamber open on one side and at the bottom of the stock, a unitary ammunition tape feeding and firing mechanism mounted in said breech chamber, and adapted for loading on the open side of the breech, a plate pivoted on the stock for closing the said breech openings, the swinging end having a clamp fitting around the stock with a thumb piece for opening, and a rifle barrel secured 70 to the stock and having its rear end communicating with said breech chamber.

4. In a toy repeating rifle, the combination of a stock formed with a breech chamber open at one side and at the bottom, an ammunition tape feeding and firing mechanism mounted in said chamber, and adapted for loading on the open side of the breech, a breech plate swiveled to the stock for closing the side and bottom of the breech chamber, 80 the bottom portion being provided with an opening for the trigger projection and for the escape of exploded tape, the moving end of said plate having a clamp fitting over the stock and a thumb piece for opening, a rifle 85 barrel, the rear end of which is partially cylindrical and secured to the breech portion of the stock, the upper wall of the breech chamber providing a communication with the rear end of the rifle barrel.

5. In a toy repeating rifle, the combination of a rifle stock formed with a breech chamber open on one side and at the bottom, and formed with a vertical slot in its upper wall, a unitary ammunition tape feeding and firing mechanism supported in said breech chamber and adapted to be loaded from the open side, a plate swiveled to the stock for closing the said bottom and side openings of the breech chamber through which the trigger projects, the moving end of said plate having a clamp fitting upon the stock and a rifle barrel having its rear end partially cylindrical, secured to the stock, inclosing the said vertical slot through the upper wall of 100 the breech chamber.

6. In a toy repeating rifle, a rifle stock formed with a breech chamber open on one side and at the bottom, an ammunition tape feeding and firing mechanism inclosed in 115 said chamber, the upper wall of the breech chamber being formed with an opening into the barrel, a plate swiveled to the stock for inclosing the side and bottom of the breech chamber through which the trigger projects, detachable connection between the stock and rear end of the plate, a rifle barrel, the front end of which is cylindrical and the rear end partially cylindrical, said rear end forming 120 a cover for said breech chamber, the front end of the stock being indented for endwise insert of the lower cylindrical portion of the barrel, and means for attaching the rear end of the barrel to the stock.

7. In a combination with the stock of a 130

- toy repeating rifle, formed with a breech chamber for supporting an ammunition tape feeding and firing mechanism, a rifle barrel attachable to the stock, consisting of sheet metal rolled upon itself at the front end into a barrel with the rear end partially cylindrical, and adapted to cover the breech chamber, the margins of the cylindrical portion of the barrel being overlapped and the metal 5 at the muzzle end being bent inwardly upon itself, forming a round smooth muzzle, of lesser diameter than the internal diameter of the barrel.
8. In a toy repeating rifle, the combination of a stock formed with a breech chamber, having an open portion for loading, a closure member on the stock, and tape feeding and firing mechanism in the breech chamber, a sheet metal rifle barrel having its 10 front end cylindrical and its rear end partially cylindrical and covering the breech chamber, and means constituting an endwise attachment of the cylindrical portion of the barrel to the stock.
25. 9. In a toy repeating rifle, a stock formed with a breech portion, open at one side and at the bottom, a movable member attached
- to the stock for covering the breech chamber, the bottom portion providing openings for the trigger and for the escape of exploded 30 tape, tape feeding and firing mechanism in said breech chamber adapted for loading on the open side of the chamber to discharge the tape at the bottom of the breech chamber, and a rifle barrel secured to the stock, 35 having its rear end covering and communicating with said breech chamber.
10. In a toy repeating rifle, a stock having a recess in one side to provide a breech chamber, a barrel having a tubular forward portion and a semi-tubular rearward portion, 40 said rearward portion secured upon said stock and covering the one end of said chamber, an ammunition tape feeding and exploding mechanism mounted in said chamber, and a hinged closure member covering said recess and mechanism within said recess. 45

In witness whereof I hereunto subscribe my name, as attested by the two subscribing witnesses.
